UNITED STATES PATENT OFFICE.

GEORGE WASHINGTON BONDS, OF SAN FRANCISCO, CALIFORNIA, ASSIGNOR
TO BYRON JACKSON, OF SAME PLACE.

FRICITION-CLUTCH.

SPECIFICATION forming part of Letters Patent No. 313,284, dated March 3, 1885.

Application filed August 29, 1884. (No model.)

To all whom it may concern:

Be it known that I, GEORGE W. BONDS, of the city and county of San Francisco, and State of California, have invented an Improvement 5 in Friction-Clutches; and I hereby declare the following to be a full, clear, and exact description thereof.

My invention relates to a friction-clutch for hoisting-drums, pulley-shaft couplings, &c., 10 and it is more especially applicable to what are known as "wagon-derricks," in which winding-drums are employed for operating derrick-forks.

It consists in a means for applying the clutching device so that the strain is applied without any pressure upon the journals, and in 15 certain details of construction, all of which will be more fully explained by reference to the accompanying drawings, in which—

20 Figure 1 is a vertical longitudinal section taken through the axis of the drum. Fig. 2 is a transverse section showing the clutch mechanism. Fig. 3 is a plan view of the drums and horizontal section of the clutch. 25 Figs. 4, 5, 6, 7, 8, and 9 are details of the several parts of the clutch.

A is a frame-work, upon which, in the present case, I have shown the journal-boxes B supported. The shaft C may turn in these 30 journal-boxes, and the drums D are loosely supported upon this shaft. Between these drums is a friction-wheel, E, which may be keyed to the shaft C, or it may run loosely thereon, and has a beveled gear-wheel, E', secured to one side. A beveled pinion, F, fixed 35 to the shaft G, meshes with the gear E', so as to drive and rotate it. This shaft G is driven by a pulley, H, or other suitable device, and the wheel or drum E is thus driven from its 40 periphery and not from the shaft C.

To the heads of the drums D which are adjacent to the pulley E are hinged two castings, I, having friction-blocks K, which may be made either of wood or metal, secured to them. The hinge-pins I' of these castings are 45 near one side of the circumference, while the opposite ends extend nearly to the other side, and are driven toward each other by a spiral or other spring, L, which tends to keep the 50 friction-blocks K out of contact with the in-

terior periphery of the wheel or rim E. Lugs a project from the inner sides of the castings I at points upon the opposite side of the shaft C from the hinge-pins I', and these lugs have their faces inclined, so that a wedge-shaped 55 block, M, may fit and slide between them. This block has an extension from its smaller end, which passes out through the head of the drum D, and is connected with the sliding collar N, so that it may be moved to or from the 60 end of the drum.

O is a clutch-lever connected with this collar and having its fulcrum upon the support P, which may be secured to the box or other suitable point. 65

The operation will then be as follows. When the wedge-block M is pushed inward, the spring L will draw the free ends of the castings I toward each other, so as to hold the frictional blocks K out of contact with the interior of the drum E; but when it is desired to have the drum rotate, the lever O is moved so as to draw the wedge-block M between the lugs a, and by pressing these lugs and the casting I outward it forces the blocks K against 70 the interior of the rim E, so that the friction will be sufficient to set the drum in motion and cause it to revolve, thus winding the rope upon it as long as may be desired. By moving the lever O in the opposite direction the 75 wedge M is forced back and the frictional blocks released, when the drum will stop.

Each of the drums D has a similar device for operating it, so that either one or both may be operated. 85

The drums may be supplied with the usual brake straps and levers for holding them at any point and suspending the load or for easing it back; or the clutch-lever alone may be used in the case of light loads. 90

An important feature of my invention is the driving of the intermediate friction-wheel, E, from the periphery and independently of the shaft C, so that the latter may turn with it; or it may be fixed and the wheel and drums both 95 turn upon it.

Having thus described my invention, what I claim as new, and desire to secure by Letters Patent, is—

1. In a hoisting apparatus, the shaft having 100

the wheel or rim upon it, a winding-drum turning loosely upon the shaft and having frictional blocks upon the opposite sides of the shaft, together with a wedge which may be drawn between these blocks, so as to force them outward into contact with the rim, substantially as herein described.

2. In a hoisting apparatus, the winding-drum turning loosely upon the shaft, with one end adjacent to a wheel which is upon said shaft, friction-blocks hung upon the end of the drum, so that their faces are in proximity with the interior of the wheel-rim, and a wedge which may be moved between these friction-blocks or their supporting-hangers, together with an operating-lever and collar, substantially as herein described.

3. In a hoisting apparatus, the rope-winding drums, with an intermediate friction-wheel mounted upon a shaft and a peripheral gear

upon the friction-wheel, by which the latter is driven, substantially as described.

4. In a friction-clutch, a wheel or rim upon the shaft and having suitable driving-gear, a drum or drums turning loosely upon said shaft and having one end adjacent to the wheel, friction blocks or shoes supported upon the end of the drum, so that their faces may be forced outward against the rim of the wheel, a wedge-shaped block moving between these shoes or their supports, together with an actuating-lever, by which it may be moved, and the retracting-spring L, substantially as herein described.

In witness whereof I have hereunto set my hand.

GEORGE WASHINGTON BONDS.
